UNITED STATES PATENT OFFICE.

GUSTAV A. BRACHHAUSEN, OF RAHWAY, NEW JERSEY.

MOTOR MECHANISM.

SPECIFICATION forming part of Letters Patent No. 657,756, dated September 11, 1900.

Original application filed April 4, 1900, Serial No. 11,415. Divided and this application filed June 7, 1900. Serial No. 19,347. (No model.)

To all whom it may concern:

Be it known that I, GUSTAV A. BRACHHAUSEN, a citizen of the United States, residing at Rahway, Union county, State of New Jersey, have invented certain new and useful Improvements in Motor Mechanism, of which the following is a specification.

My present invention relates to motor mechanism, and more particularly to spring-motors for musical and like instruments.

Considerable difficulty has been experienced heretofore in musical instruments and other devices by reason of the fact that the sudden release of the parts of the motor mechanism usually resulted in injuring the entire instrument.

The object of my invention is to overcome these difficulties and to provide a motor mechanism wherein no injurious results to the entire device are liable to follow the sudden release of the parts—such, for instance, as that which follows from breaking the mainspring of the motor or some of the teeth of the connecting-gears.

To these ends my invention consists in the novel arrangement and combination of parts to be hereinafter described and claimed.

In the accompanying drawings, Figure 1 represents a rear view of sufficient number of parts of a mechanical musical instrument to illustrate my invention. Fig. 2 is a fragmentary enlarged detail view of a portion of the structure to be hereinafter more fully described. Fig. 3 is a side view of the spring-drum of the motor. Fig. 4 is an end view of the same looking in the direction of the arrow in Fig. 1.

1 designates the framing of the instrument in which the various parts are mounted. To 40 this framing is secured a casting 2, which constitutes a bearing for various portions of the device. A spindle 3 projects from the casting, and upon this spindle rotates a spring-drum 4. The spring-drum 4 is provided with 45 a driving-gear 5 and a cam-plate 6. The spring of the drum 4 is wound by a key-post 7, which is adapted to project through the casting 2 and is provided at its inner end with a pinion 8. This pinion 8 is adapted to 50 engage an internal gear 9. The periphery of

this internal gear 9 is formed as a ratchet-wheel 10, and a suitable locking-pawl (not shown) is provided to engage the ratchet-wheel to prevent a backward movement thereof. The combined internal gear and 55 ratchet-wheel 9 10 is connected to the inner end of the spring in any suitable manner, so that a rotation of the winding-post 7 will cause the spring to be wound. The cam-plate 6 is provided with cams or indentures 60 11 12 in the periphery thereof for transmitting motion to various portions of the instrument. Thus the cam 11 co-operates with an antifriction-roller 13, carried by an arm 14, which is secured to a rock-shaft 15. This 65 rock-shaft is likewise provided with one or more arms 16, which transmit longitudinal motion to a rod 17 through the intermediate abutment 18. The shaft 15 is likewise provided with a crank-arm 19, that is adapted 70 to transmit motion to portions of the instrument upon an oscillation of the shaft 15 in the manner described.

For a thorough understanding of the present invention it is unnecessary to enter into 75 details as to the various operations produced by the movement of the parts hereinbefore described, it being sufficient that it be understood that the cam-plate 6 transmits motion to various portions of the device. The driving-gear 5 is connected up with a train of gear to the governor in the usual or any ordinary manner and which needs no illustration for a thorough understanding of the present invention. 80

Reference being had to Figs. 2, 3, and 4 of the drawings, it will be observed that the driving-gear 5 and the cam-plate 6 are movably connected to the spring-drum 4—that is to say, the cam-plate and gear are made in separate pieces from the drum and are united thereto, so as to be capable of attaining a partial rotation independently of the spring-drum 4. In the present instance I have provided inclined pins or projections 20 upon 95 the gear or driving wheel 5. The pins or projections 20 project into undercut elongated grooves 21, formed in the drum, as indicated at the upper right-hand portion of Fig. 3 of the drawings. The length of each of the 100

grooves 21 is considerably greater than the pins or projections are thick, so as to permit a free movement or backlash of the gear with relation to the drum. By inclining the pins 5 in the manner stated the gear cannot be removed from the drum, but merely has a slight rotary movement independent thereof. The cam-piece 6 is connected with the drum in substantially the same manner as the gear-wheel 5. Thus the cam-piece is made of a separate piece from the drum and carries projections or pins 22, which are inclined and project into undercut elongated recesses 23, formed in the drum. The length of these recesses is such as to permit a free movement 10 of the pins 22 therein, so that a free movement or backlash of the parts with relation to each other may be provided in case the spring of the drum is broken. The backlash 15 of these parts prevents injury to the device as a whole in case of a sudden releasing of the parts.

It will be understood that in operation motion is communicated to various portions of 25 the device through the gear 5 and the cam-plate 6 when the motor is in operation and that a sudden releasing of the parts by a breaking of the spring in the drum 4 or by damage to the teeth of any of the gear-wheels 30 35 will permit a backlash of the spring-drum 4 and cam-plate 6 and gear 5 with relation to each other, so as to prevent injury to the entire device.

It is thought from the foregoing description that a clear understanding of the invention can be arrived at without a further detail description of the construction and operation of the device.

The subject-matter of the present application is a division of my application, Serial No. 40 11,415, filed April 4, 1900, for automatic mechanical musical instruments.

Having described my invention, what I claim, and desire to secure by Letters Patent, 45 is—

1. In a spring-motor, the combination of a spring-drum, hand-operated means for winding the spring of said drum and retaining it against backward movement and a driving-gear 50 operatively connected thereto to rotate therewith, said driving-gear being rotatable with said drum in one direction but capable of movement independently of said drum in an opposite direction.

2. In a spring-motor, the combination of a spring-drum, hand-operated means for winding the spring of said drum and retaining it against backward movement, a driving-gear adapted to rotate with said drum in one direction to effect a movement of the movable parts and a pin-and-slot connection between said drum and gear to permit an independent movement of said drum and gear with

relation to each other in an opposite direction.

3. In a spring-motor, the combination of a spring-drum, hand-operated means for winding the spring of said drum and retaining it against backward movement, a driving-gear adapted to rotate therewith to effect a movement of the movable parts of the instrument, inclined pins or projections extending from said gear and coöperating with undercut grooves in the drum into which said pins project to prevent the gear from being removed from the drum but to permit an independent movement of the drum and gear with relation to each other.

4. In a spring-motor, the combination of a spring-drum, hand-operated means for winding the spring of said drum and retaining it against backward movement, a driving-gear adapted to rotate with said drum in one direction to effect a movement of the movable parts of the instrument, inclined pins or projections extending from said gear and coöperating with undercut grooves in the drum into which grooves said pins project to prevent the gear from being removed from the drum but to permit an independent movement of the drum and gear with relation to each other, a cam-plate adapted to rotate with the drum to effect a movement of the movable parts, inclined pins or projections carried by said cam-plate, undercut grooves in the drum and into which grooves the pins on the cam-plate are adapted to project to prevent the cam-plate from being removed from the drum but to cause said drum and cam-plate to move together in one direction but to permit an independent movement of the drum and cam-plate with relation to each other in an opposite direction.

5. In a spring-motor, the combination of a spring-drum, hand-operated means for winding said drum and a driving-gear and a cam-plate operatively connected to rotate with the drum in one direction, said driving-gear and cam-plate being capable of movement independently of said drum in an opposite direction.

6. In a spring-motor, the combination of a spring-drum, hand-operated means for winding said drum, a driving-gear adapted to rotate with said drum in one direction to effect a movement of the movable parts, a cam-plate and pin-and-slot connection between said drum and gear and between the drum and cam-plate to permit an independent movement of said drum, gear and cam-plate with relation to one another in an opposite direction.
